US0D1004696S

(12) **United States Design Patent** (10) **Patent No.:** **US D1,004,696 S**
(45) **Date of Patent:** **** Nov. 14, 2023**

(54) **MEDIA PROCESSING DEVICE**

(71) Applicant: **ZEBRA TECHNOLOGIES CORPORATION**, Lincolnshire, IL (US)

(72) Inventors: **James Lucas**, Coventry, RI (US); **Anthony Ross Helberg**, Attleboro, MA (US)

(73) Assignee: **Zebra Technologies Corporation**, Lincolnshire, IL (US)

(**) Term: **15 Years**

(21) Appl. No.: **29/811,026**

(22) Filed: **Oct. 11, 2021**

Related U.S. Application Data

(63) Continuation of application No. 29/693,076, filed on May 30, 2019, now Pat. No. Des. 935,522.

Primary Examiner — Lauren D McVey

CLAIM

We claim the ornamental design for a media processing device, as shown and described.

DESCRIPTION

FIG. 1 is a first top perspective view of a media processing device;

FIG. 2 is a second top perspective view thereof;

FIG. 3 is a first bottom perspective view thereof;

FIG. 4 a top plan view thereof;

FIG. 5 is a bottom plan view thereof;

FIG. 6 is a first side view thereof;

FIG. 7 is a second side view thereof;

FIG. 8 is a rear view thereof;

FIG. 9 is a front view thereof; and,

FIG. 10 is a second bottom perspective view thereof.

Broken lines are for purposes of illustrating environment and form no part of the claimed design.

The wire frame lines shown throughout the views indicate surface contour.

1 Claim, 9 Drawing Sheets
